DIE

George W. Stockburger, Philadelphia, Pa.

Substituted for abandoned application Serial No.
732,553, March 5, 1947. This application July
9, 1951, Serial No. 235,865

6 Claims. (Cl. 226—86)

1

This invention relates to improvements in dies that can be used to affix closures to containers. More particularly, this invention relates to an improved die that can be used to press and heat-seal closures onto containers.

It is therefore an object of the present invention to provide an improved die that can be used to press and heat-seal closures onto containers.

The problem of providing readily removable, liquid-tight closures for containers is one which has vexed manufacturers, suppliers and users of containers for many years. The closures must adhere tightly to the containers to prevent efflux of the contents and to prevent influx of foreign matter, and yet they must be readily removable by the ultimate consumer's hands or by the simple tools available to the ultimate consumer. Some of the closures have had discs of cork or other resilient material which were held in contact with the mouths of the containers by metal caps that fitted over the outsides of the containers. Others consisted of circular discs that fitted recesses adjacent the mouths of the containers, and those closures were held in place by friction. Still other closures were hood-like in form and fitted over the necks of the containers; and those closures were held in place by being crimped or pressed against the containers. In addition, closures have been used that were of resilient material and fitted into or over the mouths of containers and were held in place by friction. Each of these various closures is usable with varying degrees of success, but none of them is completely satisfactory from the standpoints of cost, tightness, ready removability, and protection against contamination of the contents of the containers. As a result, a definite need existed for an improved closure for containers; that need was met by the invention disclosed in my application for Letters Patent, Serial No. 772,378, for Receptacle Closure, now Patent No. 2,586,446.

When closures, made in accordance with said invention, are pressed against containers in the presence of heat, those closures become firmly sealed and attached to the containers in such a way that they completely protect the contents of the containers but are themselves readily removed from the containers when desired. Those closures must be heated as they are pressed firmly against the containers, and this requirement necessitates the application of appreciable amounts of heat and pressure to the closures and containers. The applications of heat and pressure must be large enough to permit rapid application and sealing of the closures to the containers

2

but must be small enough to avoid injury to the containers. It is therefore necessary to have a heated die that provides a firm, controlled pressure against the closures while the closures are heated to the required temperature. The present invention provides such a die and it is therefore an object of the present invention to provide a die that heats closures for containers while applying a firm, controlled pressure to those closures.

The die provided by the present invention has a closure-receiving recess and a number of extensible and retractable fingers adjacent that recess. The fingers and the recess are suitably heated and serve to apply heat to the top and sides of the closures, thus insuring rapid and even heating of the closures. This facilitates the attainment of a good seal between the closures and the containers and also permits rapid application of the closures to the containers. It is therefore an object of the present invention to provide a die that has a heated recess to act against the tops of closures and has heated fingers to act against the sides of the closures.

Containers which hold their contents under pressure, and are closed by readily removable closures, are generally provided with enlarged portions adjacent the mouths thereof, and those enlarged portions are useful in facilitating the securing of closures to the containers. For example, in many instances the lower portions of the containers are initially provided with inner diameters greater than the outer diameters of the enlarged portions of the containers and, during the operation wherein the closures are affixed to the containers, the lower portions of the closures are slipped over the enlarged portions of the containers and are then made to have inner diameters which are smaller than the outer diameters of the enlarged portions of the containers; this prevents undesired separation of the closures from the containers. Where the closures are made of flexible material, as are the closures of my application Serial No. 772,378, it is desirable to iron and smooth the lower portions of the closures against the containers. The die of the present invention acts to iron and smooth the lower portions of the closures against the containers by providing a plurality of circumferentially spaced, radially acting fingers that urge the lower portions of the closures against the containers. These fingers are not confined in guides but are free to move circumferentially as well as radially and this circumferential movement facilitates smoothing and ironing of the

lower portions of the closures onto the containers. Where the lower portions of the closures are initially provided with wrinkles or crimps to facilitate smooth and ready securement of the lower portions of the closures to the containers below the enlarged portions adjacent the mouths of the containers, the wrinkles or crimps will initially present an uneven surface to the fingers and will cause circumferential movement of those fingers, thus providing an ironing and smoothing action. It is therefore an object of the present invention to provide a die with a plurality of radially and circumferentially movable fingers.

In securing closures to containers by the use of pressure and heat it is necessary to force the closures against the containers without delay and then to hold the closures against the containers by means of pressure until the closures are firmly sealed to the containers. These considerations must be coupled with the consideration of cushioning the force applied to the closures and to the containers. The die provided by the present invention affords prompt contact between the pressure-applying fingers and the closures and yet cushions the force applied by those fingers to the closures and containers by providing a plurality of cams that pass between spring-biased pins and the pressure-applying fingers. The cams cooperate with the spring-biased pins to move the fingers toward the containers without delay but the springs that act upon the pins will yield before the forces on the fingers can increase to values at which the containers would be injured. It is therefore an object of the present invention to provide a die which has a number of cams that pass between spring-biased pins and pressure-applying fingers.

Where a die is used to apply closures to bottles containing comestibles, as in a dairy or brewery, it is of the utmost importance that the die have its parts readily accessible for cleaning purposes. Moreover, it is important that no part of the die have a configuration or form which would cause it to catch and hold dirt or other foreign matter. The present invention provides such a die by having all parts thereof free-draining and readily washable. It is therefore an object of the present invention to have a die which has all parts thereof of free-draining and readily washable.

Many closures for containers consist of a pre-formed metal cup that is provided with an inner disc of resilient material. In applying such closures to containers it is only necessary to place the closures on the tops of the containers and strike them with an uninterrupted annulus. Such dies can be made quite compactly and in many instances machines are made which have a number of such dies in closely spaced relation. In order to replace the closures and dies of this type, it is necessary that a new closure and the die therefor be of such size that a number of the dies can be inserted and operated in the machines built for the present annulus type of dies. The present invention provides such a die by utilizing a compact housing that supports the movable fingers and has leaf springs mounted on the exterior thereof to bias the pins carried by the housing.

Other and further objects and advantages of the present invention should become apparent from the drawing and accompanying description.

In the drawing and accompanying description a preferred embodiment of the present invention is shown and described but it is to be understood

that the drawing and accompanying description are for the purposes of illustration only and do not limit the invention and that the invention will be defined by the appended claims.

5 In the drawings,

Fig. 3 is a plan view of the cup-shaped housing of Fig. 2, and it shows the fingers or jaws of the die in retracted position within said housing.

15 Fig. 4 is a plan view of one of the fingers or jaws shown in Fig. 3.

Fig. 5 is a side elevational view of the fingers or jaws shown in Fig. 4.

20 Fig. 6 is a side elevational view of a castellated member which is normally positioned within the cup-shaped housing of Fig. 2.

Fig. 7 is a plan view of the castellated member shown in Fig. 6.

Fig. 8 is a bottom view of the die shown in Fig. 1.

25 Fig. 9 is a plan view of a cam carrier used with the die of Fig. 1.

Fig. 10 is a side elevational view of the cam carrier of Fig. 9, and

30 Fig. 11 is a vertical central sectional view of the die shown in Fig. 1.

Referring to the drawing in detail, the numeral 20 denotes a cup-shaped housing that is a part of a die made in accordance with the principles and teachings of the present invention.

35 The cup-shaped housing 20 has a central opening 22 in the bottom thereof, and it also has a plurality of circumferentially spaced openings 24 in the bottom thereof. The central opening 22 will be dimensioned to receive the mouth of the

40 container that is to be provided with a closure and the mouth of that container will extend up through the opening 22 into the space within the housing 20. The die provided by the present invention can apply and seal closures to beer bottles, milk bottles, jelly glasses, fruit jars, metal or earthenware containers, and to many other types and kinds of containers, and in each case the opening 22 in the housing 20 will be dimensioned to receive the mouth of the container with which the die is to be used.

45 The openings 24 are spaced outwardly from the central opening 22, and they are all equidistant from the geometric center of the housing 20. A number of radially-disposed, smooth-bore, circular openings 26 are provided in the side wall of the housing 20, and those openings receive reciprocating pins 28. The openings 26 are located at the ends of radii which pass through the openings 24 and the inner ends of the pins 28 overlie the circumferentially spaced openings 24.

50 The outer ends of the pins 28 are provided with enlarged heads that will not pass through the openings 26 in the wall of the housing 20, and those heads limit inward movement of the pins 28 to a predetermined distance.

55 A number of radially-disposed, threaded openings 30 are provided in the wall of the cup-shaped housing 20, and those openings are spaced vertically above the pin-receiving openings 26. The openings 30 receive machine screws 32 and the screws 32 extend through openings in the upper ends of flat leaf springs 34 to maintain those springs in assembled relation with the housing 20. Each of the springs 34 is shown as a single leaf. Where

60 desired, other types of springs can be used but

65

70

75

leaf springs are preferred as the most desirable from the standpoints of compactness, length of life, and cleanliness of operation. The leaf springs 34 are suitably spaced outwardly from the wall of the cup-shaped housing 20 by washers 36 which are placed adjacent the inner and outer surfaces of the springs 34. The leaf springs 34 are vertically disposed and they are dimensioned so the lower ends thereof extend to and bear against the outer ends of the pins 28. The wall of the housing 20 is also provided with circumferentially-spaced, radially-disposed, threaded openings 38 and those openings receive machine screws 40.

The inner surface of the bottom of the housing 20 is made smooth, and that surface receives a plurality of individual fingers or jaws 42. Each of these fingers or jaws 42 has a multi-planar arcuate inner periphery 44 and a slotted outer periphery 46. A slot 48 is provided in the outer periphery 46 of each finger or jaw 42, and each of the slots 48 terminates in a bi-planar surface 50. The sides of the fingers or jaws 42 are plane and they are inclined relative to each other. Openings 52 are provided in the sides of the jaws 42, and those openings are in register with the openings 52 of adjacent fingers or jaws 42. The openings 52 in the jaws 42 are dimensioned to receive small diameter, helical springs 54 and the springs 54 are dimensioned to extend between adjacent jaws or fingers 42, as shown in Fig. 3. These fingers or jaws 42 are particularly usable in sealing closures to containers which have enlarged portions adjacent the mouths thereof, because the innermost portions of the multiplanar peripheries 44 will press the closures against the lower sections of those enlarged portions. Where the die is used to apply and seal closures to containers which are not provided with enlarged portions adjacent the mouths thereof, the inner periphery of each of the fingers 42 may have a different surface than that shown in the drawings and with a smooth-walled container, the inner peripheries of the fingers 42 may be smooth. In each instance, the inner peripheries of the fingers 42 should be complementary to the outer periphery of the container so they can press the closure tightly against the container.

The fingers or jaws 42 can be made in various ways but they must be made so they can be brought together to press a closure against a container. Moreover, the fingers or jaws 42 must be made so they can apply smooth and uniform pressure around the entire periphery of the closure and container. One certain and simple way of making the jaws 42 is to machine an annulus with an inner diameter equal to the outer diameter of a closure that is sealed onto a container and thereafter to cut along radii of the annulus to form the fingers or jaws 42. Where this is done the fingers 42 can be held in retracted position, as shown in Fig. 3, to permit the insertion and removal of a container and closure through the opening 22 in the cup-like housing 20; or the fingers can be moved to extended position to again form an annulus with an inner diameter equal to the outer diameter of a closure that is sealed to a container. In making the fingers or jaws 42 in this manner, openings 56 are formed in the annulus to secure it to the metal working machine and those openings are shown in several of the fingers 42.

The multi-planar inner periphery 44 of each of the fingers or jaws 42 is dimensioned to press a portion of a closure into sealing engagement with

the enlarged portion of a container, and those peripheries 44 cooperate to press all sides of the closures into sealing engagement with the containers. The outer peripheries 46 of the fingers or jaws 42 are made to have configurations approximately complementary to the inner surface of the wall of housing 20; therefore the fingers can be pressed against that wall and still maintain their proper position and orientation. The slots 48 in the rear peripheries 46 of the fingers 42 are dimensioned to receive and telescope over the inner ends of the pins 28, but the slots 48 are so much wider than the pins 28 that the pins do not impede radial movement of the fingers 42. 15 The fingers or jaws 42 can move radially and circumferentially of the housing 20 since the upper surface of the bottom of that housing is plane and smooth and since the fingers 42 are biased apart as shown in Fig. 3. The springs 54, 20 which are seated in the openings 52 in the sides of the jaws 42 and which extend between adjacent fingers or jaws 42, act to bias the jaws 42 for movement away from each other and radially outwardly against the wall of the housing 20, but 25 they are compressible and extensible to permit the fingers or jaws 42 to move toward and away from each other. The pins 28, which extend into the slots 48 in the outer peripheries 46 of the fingers or jaws 42 will limit, but will not prevent, circumferential movement of the fingers 42 when those 30 fingers are in retracted position. As a result, while the fingers or jaws 42 will normally be held approximately in the position shown in Fig. 3, they will be movable radially and circumferentially relative to that position.

A castellated member is denoted by the numeral 58, and that member has a series of axially-extending, radially-disposed slots 60 that provide the castellated formation for the member 58. A 40 circular recess 59 is provided in the under side of the member 58, and that recess can receive and fit over the top of a closure for containers. Many containers that receive closures, are provided with smoothly rounded mouths; and as a 45 result the edges of the recess 59 are smoothly rounded. Where the mouths of the containers are not smoothly rounded, the edges of recess 59 need not be so rounded. The castellated member 58 is dimensioned to fit snugly within the 50 cup-shaped housing 20; and threaded openings 61 are provided in the member 58 to receive machine screws 40 that will hold the housing 20 and the castellated member 58 in assembled relation. A central rod 67 is integrally secured to the castellated member 58, and the upper end of that rod 55 extends above the rest of the member 58. An opening 68 is provided in the rod 67.

A heating element H, such as an electrical resistance heater which is provided with leads 64 and 66, is positioned within an annular piece of metal 62; and the annulus 62 is intimately secured to the castellated member 58 by machine screws 63. The heating element H will heat the surface of the recess 59 as well as all other 60 parts of the castellated member 58; and since the castellated member 58 is snugly fitted inside of the housing 20, heat from the heating element H will enter and heat the housing 20.

The rod 67 is dimensioned to fit within the axial recess 70 of a hollow rod 71 that is a part of the cam carrier shown in Figs. 9 and 10. The rod 67 and the recess 70 in the rod 71 are dimensioned to permit ready telescoping movement of the rods 67 and 71. The rod 71 is provided with a slot 72 that extends through to the recess 70,

and that slot receives a pin 74 carried by the transverse opening 68 in the rod 67 of castellated member 58. A collar 76 is mounted on the rod 71 of the cam carrier, and it is normally maintained in position on that rod by a set screw 77^a, which is seated in the threaded opening 77. The cam carrier has a transversely extending flange 78 which is integrally secured to the hollow rod 71 and the flange 78 is provided with a plurality of radially-disposed, circumferentially-spaced slots 80. The slots 80 receive the upper ends of vertically-disposed, elongated cams 82, and pins 84 are provided that extend through the upper ends of cams 82 and extend to the walls of the slots 80. The pins 84 maintain the cams 82 in assembled relation with the cam carrier while permitting swinging of the cams 82 relative to the cam carrier. Each of the cams 82 has an inner cam surface 85 and an outer cam surface 86. The inner cam surface 85 has a relatively steep cam face which provides quick actuation, and the outer cam surface 86 has a relatively shallow cam face that provides slower actuation.

The cams 82, that are pivoted to the flange 78 of the cam carrier by the pins 84, can swing about the axes provided by those pins. In addition, by reason of machining tolerances, the cams 82 will be able to tilt slightly from side to side. This tilting of the cams will be limited, but not completely prevented, by the castellated portions of the member 58 that form the slots 68. Consequently, even when the cams 82 are in the position shown in Fig. 1, those cams can tilt to a limited degree. The lower ends of the cams 82 extend into the slots 48 in the outer peripheries 46 of the fingers or jaws 42 and the slots 48 are dimensioned relative to the ends of the cams 82 to permit tilting of the cams 82 relative to the fingers 42 and to permit limited circumferential movement of the fingers or jaws 42 relative to the cams 82. The inner cam surfaces 85 will bear against the biplanar surfaces 50 at the inner ends of the slots 48 of the jaws 42, and the outer cam surfaces 86 will bear against the inner ends of the pins 28 during the operation, wherein a closure is affixed to a container. The cams 82 are so dimensioned relative to the fingers 42 and the pins 28 that when the fingers or jaws 42 are in retracted position, as shown in Fig. 3, the cams 82 will not press against the biplanar surfaces 50 at the inner ends of the slots 48 of the fingers 42. This initial spacing between the cams 82 and the surfaces 50 is due to the fact that the enlarged heads of the pins 28, which are held against the wall of the housing 20 by the leaf springs 34, act to hold the inner ends of the pins 28 against further inward movement; that spacing is also due to the fact that the depth of the slots 48 is greater than the combined length of the pins 28 and the width of the small-thickness ends of cams 82. As a result, when the jaws 42 are in retracted position, the outer peripheries 46 thereof can bear against the inner surface of the wall of the housing 20 and this arrangement facilitates the maintenance of the fingers 42 in properly oriented position relative to the opening 22 in the housing 20. The outer peripheries 46 of the fingers or jaws 42 are cut to a smaller radius than is the inner surface of the housing 20, but that difference has not been found to cause improper orientation of the jaws 42.

In assembling the various elements of the die, the pins 28 are seated in the opening 26 of the housing 20, and the leaf springs 34 and washers 26 are secured to the housing 20, by the machine

75 screws 32. The fingers or jaws 42 are then placed within the housing 20 so the slots 48 thereof telescope over the inner ends of the pins 28, and the springs 54 are compressed and slipped into the openings 52 of jaws 42. Thereafter, the castellated member 58, which has had the heater-containing annulus 62 secured thereto by screws 63, is telescoped within the housing 20. The screws 49 are then rotated until they seat in the openings 38 and 64, thus securing the castellated member 58 and the housing 20 together. Once this has been done, a compression spring 69 is placed within recess 70 of the rod 71 and the cam carrier, with its previously attached cams 82, is lowered until the recess 70 telescopes over the rod 67 and until the cams 82 pass through the slots 68 and extend between the pins 28 and the surfaces 50. A slight downward force is exerted on the upper end of rod 71 to compress the spring 69 in the recess 70 and to bring the opening 68 in register with the slot 72; at this time the pin 74 is passed through the slot 72 into the opening 68. The collar 76 is thereupon secured to the rod 71, and the die is ready for use. The pin 74 and the slot 72 hold the elements of the die in assembled relation but permit reciprocation of the cam carrier relative to the castellated member 58 and housing 20.

When the various elements of the die are assembled, as shown in Fig. 1, the fingers or jaws 42 are free to move to a slight extent relative to each other because of the tolerances between the cams 82 and the fingers 42, because of the tolerance between the slots 68 and the cams 82, and because of the tolerance between the cams 82 and the slots 80 of the flange 78. However, the fingers or jaws 42 will normally be at rest and will normally be held in spaced relation relative to each other by the helical springs 54 that are seated in the openings 52 in the sides of the fingers or jaws 42. The pins 28 will fit within the slots 48 of the fingers 42 and will prevent undue shifting of the fingers 42, but will not prevent slight movement of those fingers relative to each other. Similarly, the ends of the cams 82 will fit within the slots 48 in the fingers 42 and will assist in preventing undue shifting of those fingers, but will not prevent limited movement of those fingers or jaws. The leaf springs 34 will press against the enlarged heads of the pins 28 with considerable force and will tend to hold the pins 28 against movement outwardly of the housing 20, but the pins 28 are short enough so the cams 82 do not press against the fingers 42 when the cams 82 and the fingers 42 are in retracted position. The retracted position of the cam carrier and the cams 82 is attained by the compression spring that is positioned in the recess 70 of the hollow rod 71 of the cam carrier and bears against the top of the rod 67 of the castellated member 58. This spring causes the cam carrier to rise upwardly relative to the rod 67, but suitable application of force to the rod 71 will cause compression of the spring in the recess 70. When the cams 82 are in retracted position, the jaws 42 will also be in retracted position, because of the action of the helical springs 54; and in that position the fingers or jaws 42 will rest against the inner surface of the wall of the housing 20.

Upon movement of the cam carrier downwardly, as by suitable application of force to the rod 71 or the collar 76 thereon, the cams 82 will move relative to the bi-planar surfaces 50 at the inner ends of the slots 48 of the fingers or

jaws 42. The inner cam surfaces 85, which are displaced downwardly below the outer cam surfaces 86, upon the first stage of the downward movement, will cause the cams 82 to exert forces on the inner ends of the pins 28 and on the bi-planar surfaces 50 of the fingers 42. The pins 28 will be held in position by such firm pressure from the leaf springs 34 that they will not move until after the fingers or jaws 42 move; and this stage of downward movement of the cam carrier will cause the inner surfaces 85 of the cams 82 to act against the surfaces 50 and force the fingers 42 to move inwardly toward the geometric center of the housing 20. As the cam carrier continues to move downwardly, the outer cam surfaces 86 will come into action and again the pins 28 will be held against movement. Not until the fingers or jaws 42 have reached the inner limits of their travel will the pressure exerted by the cams 82 be great enough to cause the springs 34 to yield and permit outward movement of the pins 28. The outer limits of travel of the fingers or jaws 42 are determined so that there will still be slight gaps between adjacent jaws 42 when the jaws are in contact with the closure on a container that extends upwardly through the aperture 22 in the housing 20. Consequently the fingers 42 will be pressing against the closure rather than just pressing against each other. At this time the springs 54 will be wholly within the openings 52 of adjacent jaws 42.

As soon as the jaws or fingers 42 touch the closure on the container, a pressure will be applied that will press the closure tightly against the container, and when that pressure reaches a predetermined value, further inward movement of the fingers or jaws 42 will cease. Thereafter, continued downward movement of the cam carrier will force the pins 28 outwardly and will force the springs 34 to bend and yield. The cams 82 above the cam surfaces 85 and 86, are provided with gradual tapers that progressively increase the width of those cams; once the cam surfaces 85 and 86 have passed between the bi-planar surfaces of the fingers 42 and the inner surfaces of the pins 28, the tapered surfaces of the cams 82 will begin to act. Those tapers will cause further bending of the springs 34, and thus will cause the exertion of even greater pressures on the fingers 42. However, the cams 82 and spring 34 are dimensioned so even the greatest pressure exertable by the fingers or jaws 42 on a container inserted through the aperture 22 is insufficient to cause breakage, cracking or chipping of that container. The exact pressure in each instance will have to be determined in view of the size and type of closure and the size, shape and strength of the container; but springs 34 that have exerted pressures of from thirty (30) to one hundred (100) pounds have been found to be satisfactory in sealing closures to beer bottles and milk bottles.

The successive actions of the various surfaces on the cams 82 provide extremely rapid movement of the jaws 42 through the first portion of their travel, followed by a progressively slower movement of the jaws 42 as they closely approach the closure on the bottle; and then those surfaces provide an ever-increasing holding pressure that continues until the closure is firmly sealed to the container.

The circumferentially spaced openings 24 in the housing 20 are in register with the slots 48 in fingers 42 and the slots 60 in the castellated member 58, and they are also in register with

the cams 82. Consequently the cams 82 can move downwardly as far as is needed to move the fingers or jaws 42.

The heating element H carried by the castellated member 58 will heat all portions of that member, including the surfaces of the recess 59. In addition, that element will heat the housing 20 which is in intimate contact with the member 58. Moreover, heat from the bottom of the member 58 and heat from the sides and bottom of the housing 20 will pass to the fingers or jaws 42 that are immediately adjacent the member 58 and the housing 20. As a result, the fingers 42 and the recess 59 in the bottom of the castellated member 58 will possess sufficient heat to seal closures to containers as they press and hold those closures against the containers. The exact amount of heat required will vary in each case and will be determined by the size, thickness and nature of the closure, the characteristics of the adhesive or cement used with the closure, and the size, nature, and initial temperature of the containers. In most instances, the rate at which closures are to be applied and sealed to the containers will be relatively constant, and the closures, adhesives and containers will be constant; and in those cases an unregulated heating element can be used. For example, unregulated heating elements have been used to apply and affix closures to beer bottles and milk bottles. In other instances, where variables are to be expected, a rheostat or other device (not shown) can be inserted between the heating element H and the source of electricity to vary the heating effect. In addition, if desired, a thermostat (not shown) could be mounted on or in the annulus 62 to maintain the temperature of the die at a predetermined value.

Various temperatures may be used, but temperatures in the range of two hundred (200) to three hundred (300) degrees Fahrenheit have been found quite useful. Such temperatures are particularly desirable because there is no danger of burning or charring the closures if the rate at which closures are affixed and sealed to the containers is varied.

Relaxation of the force on rod 71 or collar 76 will permit the spring in the recess 70 to force the cam carrier upwardly, thus permitting the leaf springs 34 to move the pins 28 inwardly until their enlarged heads press against the wall of the housing 20, and also permitting the helical springs 54 to cause the fingers 42 to move away from the closure on the container and toward the wall of the housing 20. This permits removal of the container from the die.

As the fingers 42 move inwardly toward the closure, under the action of cams 82, those fingers may contact the closure at different times, because of slight tilting of the container or slight out-of-roundness of the closure or because the closure may be initially wrinkled or crimped to facilitate pressing it against the container while it is being sealed to the container. In such cases, the time intervals between the contacts of the jaws 42 with the various portions of the closure will be almost infinitesimal because the fingers or jaws 42 move quite rapidly; but those intervals will be large enough to permit some displacement and circumferential movement of one or more of the fingers or jaws 42. This displacement and circumferential movement can continue as the fingers or jaws 42 move radially inwardly toward the closure on the container; and in some instances the circumferential movement will occur,

because of variations in the stiffness of different sections of the closures, even though all of the jaws 42 contact the closures at the same instant. This circumferential movement of the fingers 42 is of value because it enables the fingers 42 to give an added smoothing or ironing action to the closures, thus facilitating the attainment of firm and complete seals between the closures and the containers. This circumferential movement of the fingers or jaws 42 is of course not unlimited, but it is of great value.

The large central opening 22 of the housing 20 that receives the container and the closures thereon, and the circumferentially spaced openings 24 that receive the ends of cams 82 when they move downwardly, permit cleaning and free-draining of the die in the event it is frequently washed, as it must be in a brewery, dairy, or other places where comestibles are bottled. The vertically extending slots 60 of the castellated member 58 facilitate free draining of that member, and the open character and vertical disposition of the cams 82 and leaf springs 34 promote free draining of the die. One of the few places where foreign matter could lodge is the openings 52 in the jaws or fingers 42, but the recurrent expansion and contraction of the helical springs 54 would dislodge such matter and work it out of the openings 52. Consequently, the die is exceptionally clean in operation and maintenance.

It will be noted that the fingers or jaws 42 in their retracted position, form an interrupted annulus that is coextensive with the annular bottom of the housing 20, thus obviating any wasted space. Moreover, it will be noted that the leaf springs 34 lie close to the housing 20. As a result, it is possible to make the die compact enough so it can be used with the multiple spindle machines that are presently being used to affix closures to containers.

The bi-planar surfaces 50 at the inner ends of the slots 48 of the fingers 42 facilitate the action of cams 82. The inclined portions of those surfaces cooperate with inner cam surfaces 85 to provide smooth applications of force to the fingers 42, and the vertical portions of those surfaces cooperate with the tapers of the cams 82 to exert pressure on the fingers 42 and the pins 28.

The electrical leads 64 and 66 of the heating element 62 are connected to a suitable source of current, not shown. Those leads can extend upwardly through the space between any two cams 82 and thus be free from any danger of entanglement or injury.

As the cam carrier moves downwardly relative to the housing 20, the cams 82 will rotate inwardly and cause the jaws or fingers 42 to move promptly into contact with the closures on the containers. Thereafter, as the cams 82 continue to move downwardly under the force applied to the rod 71 or collar 76 of the cam carrier, the cams 82 will swing outwardly and cause bending of the leaf springs 34. Thus the cams 82 oscillate between their inner positions and their outer positions during the operation wherein the closure is being sealed to the container; and this oscillation is of great importance because it provides quick movement of the jaws or fingers 42 against the closure and then provides a firm and controlled pressure between the jaws 42 and the closure while the closure is being sealed to the container.

Whereas a preferred embodiment of the present invention has been shown and described in the drawing and accompanying description, it

should be apparent to those skilled in the art that various changes can be made in the form of the invention without affecting the scope thereof.

This application is a substitute for my prior 5 abandoned application filed March 5, 1947, Serial No. 732,553.

I claim:

1. A die that is adapted to secure closures to containers which comprises a plurality of reciprocable fingers that are circumferentially and radially spaced to receive a container and are movable toward and away from said container, means operable to move said fingers toward said container, said means including a plurality of 10 pivotally mounted axially movable actuators that engage said fingers, said actuators being narrower than said fingers, and said fingers and actuators having interacting surfaces permitting circumferential movement of said fingers as the fingers move radially of said container, and resilient 15 members interposed between said fingers respectively and biasing them apart while permitting circumferential movement of said fingers.

2. A die for securing closures to the tops of 25 containers comprising a housing having an interior bottom wall with an opening for the reception of the top of the container, a plurality of reciprocable fingers circumferentially and radially spaced and supported by said bottom wall and 30 movable towards and away from said container top, a cam carrier vertically movable with respect to said housing and having mounted thereon a downwardly extending cam bar for each of said fingers, each of said cam bars having an outer cam surface and an inner cam surface, a resilient 35 member carried by said housing for each of said fingers, and a pin interposed between each of said resilient members and the outer cam surface of the corresponding cam bar, the inner surface of each cam bar engaging the corresponding finger for 40 moving the same inwardly.

3. A die for securing closures to the tops of 45 containers comprising a circular housing having an interior bottom wall with an axial opening for the reception of the top of the container, a plurality of reciprocable fingers circumferentially and radially spaced and supported by said bottom wall and movable towards and away from said container top, a cam carrier vertically axially movable with respect to said housing and having 50 movably mounted thereon a downwardly extending cam bar for each of said fingers, each of said cam bars having an outer cam surface and an inner cam surface, a resilient member on the exterior of said housing for each of said fingers, a pin interposed between each of said resilient 55 members and the outer cam surface of the corresponding cam bar, the inner surface of each cam bar engaging the corresponding finger for moving the same inwardly, and a plurality of resilient members interposed between said fingers and biasing them apart while permitting circumferential movement of said fingers.

4. A die for securing closures to the tops of 65 containers comprising a circular housing having an interior horizontal bottom wall with an opening for the reception of the top of the container, a plurality of reciprocable fingers circumferentially and radially spaced and supported by said bottom 70 wall and movable towards and away from said container top, a cam carrier vertically axially movable with respect to said housing and having loosely pivotally mounted thereon a downwardly extending cam bar for each of said fingers, each 75 of said cam bars having an outer cam surface at

a predetermined location and an inner cam surface at a predetermined lower location with tapered surfaces thereabove, a leaf spring mounted at one end on the exterior of said housing for each of said fingers, a pin interposed between the other end of each of said leaf springs and the outer cam surface of the corresponding cam bar, the inner surface of each cam bar engaging the corresponding finger for moving the same inwardly.

5. A die for securing closures to containers comprising a central member having an upwardly extending axially disposed rod, said member having on the lower side thereof a central recess for the reception of a closure and the mouth of a container and having on the outer portion thereof a plurality of axially extending slots, a heating element in said member above said central recess, a cam carrier mounted on said rod for axial movement, said cam carrier having mounted thereon a plurality of downwardly extending cam bars movable in said slots, said cam bars at the lower end portions having inner and outer cam surfaces with tapered surfaces thereabove, a housing having a side wall portion enclosing said central member and said cam bars and having a bottom wall with an opening for the reception of the top of the closure, a plurality of reciprocable fingers one for each of said cam bars circumferentially and radially spaced and supported by said bottom wall and movable towards and away from said closure top, each of said fingers having an inner closure engaging end and an outer end for engagement by the inner cam surface of the corresponding cam bar, a resilient member for each of said fingers mounted on said housing, and radially disposed pins interposed between each of said resilient members and the outer cam surface of the corresponding cam bar.

6. A die for securing closures to containers comprising a central member having an upwardly extending axially disposed rod, said member having on the lower side thereof a central recess

for the reception of a closure and the mouth of a container and having on the outer circumferential portion thereof a plurality of axially extending slots, a heating element in said member above said central recess, a cam carrier mounted on said rod for axial movement, a spring interposed between said rod and said cam carrier, said cam carrier having loosely pivotally mounted thereon a plurality of downwardly extending cam bars movable in said slots, said cam bars at the lower end portions having inner and outer cam surfaces with tapered surfaces thereabove, a housing having an axially extending side wall portion enclosing said central member and said cam bars and a bottom wall with an opening for the reception of the top of the closure, a plurality of reciprocable fingers one for each of said cam bars circumferentially and radially spaced and supported by said bottom wall and movable towards and away from said closure top, a plurality of resilient members interposed between said members and urging them apart, each of said fingers having an inner closure engaging end and an outer end for engagement by the inner cam surface of the corresponding cam bar, a leaf spring member for each of said fingers mounted at one end on the exterior of said side wall portion, radially disposed pins interposed between each of said resilient members and the outer cam surface of the corresponding cam bar, said pins having stops for limiting the inward movement thereof.
